[57] CLAIM

The ornamental design for a gemstone, as shown and
described.

DESCRIPTION

FIG. 1 is a top plan view of a gemstone according to a
first embodiment showing my new design;

FIG. 2 is an end elevational view thereof, the opposite
end view being a mirror image;

FIG. 3 is a side elevational view thereof, the opposite
side view being a mirror image;

FIG. 4 is a bottom plan view thereof;

FIG. 5 is a top plan view of a gemstone according to a
second embodiment of my design;

FIG. 6 is a side elevational view thereof, the opposite
side view being a mirror image;

FIG. 7 is an end elevational view thereof, the opposite
end view being a mirror image; and,

FIG. 8 is a bottom plan view thereof.

*FIG. 1**FIG. 2**FIG.3**FIG.4**FIG.5*

FIG.6
